UNITED STATES PATENT OFFICE.

MANLY M. GILLAM, OF PHILADELPHIA, PENNSYLVANIA.

ELECTROLYTIC VAPORIZER FOR MEDICINAL PURPOSES.

SPECIFICATION forming part of Letters Patent No. 366,164, dated July 5, 1887.

Application filed May 29, 1886. Serial No. 203,687. (No model.)

To all whom it may concern:

Be it known that I, MANLY M. GILLAM, of the city of Philadelphia, in the county of Philadelphia and State of Pennsylvania, have 55 invented certain new and useful Improvements in Vaporizers for Medicinal Purposes, which improvements are fully set forth in the following specification, reference being had to the accompanying drawings.

10 The object of my invention is to subject a volatile medicinal compound of an electrolytic nature to the action of voltaic or galvanic electricity in an apparatus of such size that it can easily be carried on the person, and 15 of such form that the vapor arising from such medicinal compound so treated can be conveniently controlled and applied to the nostril, eye, ear, or other part of the body.

The accompanying drawings, which represent 20 a vaporizer of the full size, will give a full comprehension of my invention and the manner of using it.

Figure 1 is a side elevation of the vaporizer. Fig. 2 is an end view, (sectional.) Fig. 3 is a 25 vertical section. Fig. 4 is a view of the metallic frame-work of the core without the absorbent wrapping or packing.

I make a tube of zinc, A, banded with copper B, and within it place a tight-fitting core 30 composed of absorbent material wrapped or packed around a coil or spiral of copper wire, C, which passes through a perforated zinc disk, D, at each end of the core, and is then bent at right angles, so as to pass along the 35 face of the zinc disk and press against the inner surface of the zinc tube A. The zinc disks fit tightly within the zinc tube. A dome-shaped cap, of copper, with a projecting small central tube, E, composed of both zinc and 40 copper and fitted with a removable stopper, cap, or cover, is tightly fastened over one end of the large tube A, and a disk, of zinc, G, having a single central opening, is tightly fitted inside and about half an inch from the other 45 end of the large tube, thus leaving a cup, H, at that extremity of the tube. I preferably make the small tube E by tightly incasing a small cylinder, of copper, with one of zinc, having a care that both metals present an even 50 terminal exposure. The cup H is formed by

the open end of the cylinder A projecting beyond the zinc disk G. The zinc cylinder at that point is encircled by one of the bands of copper, and both metals are made to present an even terminal exposure. The central opening of the zinc disk G is fitted with a thimble, 55 of copper, to give proper bearing to the stopper, cap, or cover with which the aperture is closed. The stoppered disk, of zinc, G and the stoppered dome-shaped cap, of copper, are so 60 arranged as to leave a space between each of them and the perforated zinc disks at the ends of the internal core, thus providing a chamber or reservoir, K, at each end of the large tube A.

The alternation of zinc and copper in the 65 apparatus is in the nature of a voltaic pile. When grasped in the hand, the moisture of the palm excites galvanic action between the zinc and the copper which compose the tube. Any electrolytic medicinal compound carried 70 by the absorbent material of the core also tends to excite similar action. When the end either of the small tube E or of the large tube A is made to touch the moist surface of any portion of the body, galvanic action is excited 75 between the zinc and copper which make the contact, and the entire apparatus is thereby measurably effected.

The galvanic or voltaic electricity generated in this apparatus can be plainly felt in the 80 hand and arm of any person who grasps it and who is at all sensitive to the electric current.

I claim as my invention—

A therapeutic device by means of which a medicinal compound of an electrolytic nature 85 may be subjected to the action of galvanic or voltaic electricity, which device consists of the body A, having the reservoirs K K, the cup H, the small tube E, the central core with the perforated zinc disks DD, absorbent wrapping or packing, and the central coil of copper, C, in electric contact with the zinc, and with openings in the body A at each end, having removable stoppers, caps, or covers, substantially as described.

MANLY M. GILLAM.
